John L. Highbarger,
E. W. Johnson & Co. ATTORNEYS.

UNITED STATES PATENT OFFICE.

JOHN L. HIGHBARGER, OF SHARPSBURG, MARYLAND.

CORPSE-LIFTER.

SPECIFICATION forming part of Letters Patent No. 236,949, dated January 25, 1881.

Application filed September 4, 1880. (No model.)

To all whom it may concern:

Be it known that I, JOHN L. HIGHBARGER, a citizen of the United States, residing at Sharpsburg, in the county of Washington and State of Maryland, have invented certain new and useful Improvements in Corpse-Lifters; and I do hereby declare the following to be a full, clear, and exact description of the invention, such as will enable others skilled in the art to which it appertains to make and use the same, reference being had to the accompanying drawing, and to letters or figures of reference marked thereon, which forms a part of this specification.

This invention relates to an improved implement for handling corpses, and it is designed more especially for undertakers' use when it is desirable to move a corpse or place it in a coffin; and this invention consists in providing a bar or rod with hooks, to which can be attached spring bands or straps and a flexible hood or head-rest; and it also consists in providing the head-rest with a U-shaped support, as will be hereinafter set forth.

On the annexed drawing, which is a perspective view of my invention, A represents a pole or rod, which may be hinged in the center, and is provided with knobs or handles, which may be removed for the purpose of putting on or removing the double hooks B B, which are provided with eyes which fit over the rod A, and can be adjusted laterally thereon.

The bands C C, which support the trunk of the corpse, I prefer to make of thin tempered metal, so that they can be readily slipped under the body, and when not in use they can be coiled up in a small space. These bands are provided with holes or other means of attaching them to the double hooks B B.

It is evident that the bands C C could be made of canvas or other flexible material; but if so constructed they would not be as easily placed under the corpse, and would prove a ready means of conveying disease after they had been used to carry the body of a person who had died of a contagious disease.

The head-rest D consists of a rigid U-shaped support, d, which is provided with eye-rods e for attaching it to the double hooks, and a flexible hood which may be made either of woven wire or cloth.

When it is desirable to move a corpse the hood D is placed under the head and the bands are slipped under the body, either laterally or longitudinally. The head-rest and bands are then attached to the hooks, when the body can be carried by two persons without touching it.

What I claim is—

1. The means hereinbefore described for handling and carrying corpses, consisting of the bar A, the hooks B, metallic bands C, and the flexible head-rest D, composed of the U-shaped support with eye-rods and the woven material, substantially as described. 65

2. In a device for handling corpses, a flexible head-rest, composed of the U-shaped support with eye-rods and the woven material, substantially as described.

In testimony whereof I affix my signature in presence of two witnesses.

JOHN L. HIGHBARGER.
